(No Model.)

O. RUF.
COMBINED BRIDLE FRONT AND WINKER BRACE.

No. 544,829.

Patented Aug. 20, 1895.

UNITED STATES PATENT OFFICE

OTTO RUF, OF LOS ANGELES, CALIFORNIA.

COMBINED BRIDLE-FRONT AND WINKER-BRACE.

SPECIFICATION forming part of Letters Patent No. 544,829, dated August 20, 1895.

Application filed March 29, 1895. Serial No. 543,639. (No model.)

To all whom it may concern:

Be it known that I, OTTO RUF, a citizen of the United States, residing at Los Angeles, in the county of Los Angeles and State of California, have invented a new and useful Improved Combined Bridle-Front and Winker-Brace, of which the following is a specification.

My invention is designed to provide in the harness and leather industry a long-wanted improvement, viz.: a practical and ornamental part for making a bridle hold its shape.

I am aware of the front band and winker-brace shown by L. J. Knauss and G. W. Hinckle in United States Patent No. 299,806, patented June 3, 1884, in which the winker-brace is provided with a billet formed integral therewith; and I am also aware of the brow-band and winker-brace shown in United States Patent to C. A. Harmstead, No. 348,207, patented August 31, 1886, in which the brow-band and winker-brace are made integral; but in each of these appliances there is in the middle of the leather winker-brace a flat portion which renders the leather brace liable to buckle or bend at the middle unless reinforced. Harmstead overcomes this liability by means of an additional strengthening-plate applied on the inner or under side of the winker-brace and brow-band. I wish to avoid the use of this extra plate. At the junction of each of the round side members of the brace with the flat portion and with such stiffening-plate there is necessarily an unevenness or roughness, caused by the ends of the seams of such round side members. I wish to avoid this. In the Knauss and Hinckle device the brow-band is made separate from the winker-brace and its billet and is provided on its under side with a rubber strap fastened to it by rivets and metallic plates or fastenings. I wish to avoid the use of such. In their appliance there is no means for preventing the winker-brace from bending at the places where its round side members join the billet. I wish to supply a desirable brace at this point. I am also aware of the winker-brace and bridle-front shown in United States Patent to C. C. Schwaner, No. 473,022, patented April 19, 1892, in which the winker-brace is made round continuously from end to end; but in that patent the winker-brace is

connected with the brow-band by a metal buckle which forms a projection which I wish to avoid. My invention is designed to be an improvement over all of these patented devices.

By my improvement the back of the bridle-front and winker-brace is continuous and uniform from end to end and is smooth, and the bridle-front lies smoothly around the horse's forehead, and the winker-brace is adapted to always hold the winkers or blinders exactly in the right position.

My improvement also includes in a single part a complete connection, by which the winkers or blinders, the bridle-front, and the crown-piece are braced by each other and held in their true position.

My invention relates to that class of devices which consist in a bridle-front and winker-brace virtually made in one piece.

One object of my invention is to provide a device of this kind in which the winker-brace is round continuous from one end to the other and devoid of any breaks or weak places, thus securing a more ornamental appearance and also holding the winkers or blinders more rigidly in exact position.

Another object is to provide an improved brow-piece for monograms, coat of arms, or other ornaments.

Another object of my invention is to combine in a single manufactured part a bridle-front, winker-brace, and a billet to buckle into the crown-piece of the bridle.

Another object is to make a combined bridle-front and winker-brace smooth throughout on the under side.

I accomplish the objects of my invention and overcome the said difficulties and objections pertaining to former manufactures by making the bridle-front strap of one piece with the body of the winker-brace and making such winker-brace round from end to end; and my invention comprises a combination bridle-front and winker-brace in which the strap of the bridle-front is of one piece with the body of the winker-brace, and in which the winker-brace is round from end to end virtually.

In my invention as illustrated the bridle-front strap is flat and the round winker-brace is formed of the leather integral with such

strap and continuous therewith at the middle and bent forward to form the round, so that at the middle of my appliance the winker-brace projects forward at the lower edge of the bridle-front to form the round, and provides a brace at that point, while the rear or under face of the appliance is smooth.

My invention also comprises other details and features, hereinafter set forth and claimed.

1c The accompanying drawings illustrate my invention.

Figure 1 is a perspective view of my improved combined bridle-front and winker-brace provided with center front billet for attachment with the crown-piece. Fig. 2 is a fragmental vertical mid-section of the same on a larger scale. Fig. 3 is a view of the back or under side of a bridle-front and winker-brace without such billet. Fig. 4 is a front view of the same with the brace bent. Fig. 5 is a vertical mid-section on line 5 5, Figs. 3 and 4, on a larger scale. Fig. 6 is a fragmental plan of a piece of leather ready to be formed into the winker-brace and the back or lower part of the bridle-front shown in Figs. 3 and 4. In this view the finished side of the leather—the under side of the bridle-front—is in view. Fig. 7 shows the same piece of leather turned over with the unfinished leather—the front side of the bridle-front strap—in sight, (except the loop at the left of the view,) the winker-brace filling in place, and the winker-brace strap bent and fitted to the filling ready for stitching. The left bridle-front loop is formed and the right end of the bridle-front strap is shaved, as in Fig. 6, ready to be bent to form the right loop. Fig. 8 shows, incomplete, another form with billet. In this view the winker-brace is completed, the bridle-front strap is lapped at the ends to form the bridle-front loops, and the billet-strap is pasted in place. This billet is of an economical pattern. Fig. 9 shows a billet-strap which could be substituted for the one shown in Fig. 8. Fig. 10 shows one form of the top or bridle-front waved layer for use with billet. This may be made either of harness-leather, patent-leather, or other suitable material. This waved layer is designed to cover the lap of the ends of the bridle-front strap where they are bent over to form the front loops, and it also gives stiffness to the bridle-front. The top piece for the bridle-front may be of metal plate or chain, if desired, but I prefer to make the same of leather and attach it to the bridle-front by plain or ornamental stitching. The top piece may also be ornamented by metal ornaments or by ornamental letters, coat of arms, &c., in which case the ornaments or letters would preferably be fastened to the top piece before it is stitched to the lower part.

I will now describe the manner of manufacturing my improvement. First I cut out a piece of leather (see Fig. 6) of the right length and width for forming the bridle-front and winker-brace. The length and width of

this piece of leather will vary according to the bridle to be made. The width of bridle-front will vary from one-half an inch up. 70 With a three-quarter inch front the whole width of the piece of leather would be one and one-half inches. The widths may vary, however, to suit the style of the harness. Two slits *a a'* are then made, extending from the 75 opposite ends of the piece of leather to within two inches of each other, thus leaving at the middle of the bridle-front strap A thus formed, and at its lower edge, a bridge or connection *b* connecting the bridle-front strap A 80 with the winker-brace strap B. The ends of the bridle-front strap are shaved to form the front loops. The next step is to channel the winker-brace strap B with the channels 1 2 3 85 on the finished side of the leather. The channels 1 2 extend from opposite the ends of the slits *a a'*, respectively, to near the ends, respectively, of the winker-brace strap B, but not extending to the ends of the brace-strap, for the reason that when the brace is completed the ends thereof are to be flat to fasten 90 to the winkers or blinders. The channel 3 extends along the lower edge of the winker-brace strap from end to end of the part that is designed to be round. Fig. 6 illustrates 95 the piece of leather at this stage of manufacture. The next step is to turn the straps with the unfinished side up, as shown in Fig. 7, and to bend the winker-brace strap longitudinally to receive the filling C, the length 100 of which is equal to the desired length of the round portion of the brace. The brace is then stitched from the front side, the stitches *d* running along the channels from end to end and passing through the bridge *b*, which 105 is not channeled, for the reason that the work will be stronger without channeling the bridge. The next step is to trim and blacken the winker-brace and run it through the rounder. In doing this, however, the rounder 110 will only run up to the inner ends of the slits *a a'*, and the brace along the bridge or middle piece *b* is then rounded with a hand round-finisher. The next step is to bend the rounded brace into the proper curve while it is yet 115 wet. In bending the brace it must be twisted sufficiently to bring the flat ends *e e'* into the right position to fit the blinders. Then the bridle-front strap and brace are allowed to dry. The winker-brace is now round from 120 one attachment end *e* to the other *e'*, and has the desired curve forward and downward from the front strap A. The next step is to lap and paste the front loops 4 5 at the ends of the bridle-front strap, the same being looped 125 over toward the unfinished side of the leather, as indicated in Fig. 7, by the loop 4. The next step is to fasten the bridle-front top or layer F in place on the bridle-front to cover the laps of the loops and to stiffen the bridle-front. The top or layer F, if made of leather, should be reinforced on the under side to make an oval raise and to give stiffness to the bridle, and also to increase its ornamental ap- 130

pearance. The manner of doing this and stitching the work is well understood and needs no description here. 6 in Fig. 2 and 6' in Fig. 5 indicate the reinforcing-strip.

5 In case the bridle-front is to be provided with a center front billet to connect with the crown-piece, as is preferred in some kinds of bridles, to give greater strength and rigidity and a more ornamental appearance and to 10 furnish a front on which to fasten ornaments, then the bridle-front strap is provided at its middle on the upper edge with a slight projection 7, as indicated in Fig. 8, and such strap and projection are shaved and the billet-strap G is shaved at its lower end, which 15 is made broad to fit the shape of the center ornament or waved billet-layer or top piece f. In Fig. 8 the billet-strap is shown split and filled with a wedge g for economy of 20 leather. The billet-strap is then pasted and sewed in place and covered with the top piece or waved layer F', provided with the waved billet-layer f. The top or layer F' f is fastened in place by being stitched to the 25 bridle-front and to the billet-strap.

The winker-brace, made in the manner described, being round from one flat attachment end e to the other e', gives superior stiffness and also a more ornamental appearance to 30 the bridle. The single part thus composed of the winker-brace, the bridle-front, and the center front billet gives to a bridle superior strength and rigidity, and makes it hold its shape. The billet thus attached also serves 35 for the attachment of ornaments, letters, or coat of arms.

Since the outside of the round winker-brace is formed of the leather integral with the bridle-front strap and continuous there- 40 with at the middle and bent forward, where

it joins the lower edge of the bridle-front, and there formed round, as well as throughout the rest of its length, the winker-brace at the middle of the appliance constitutes an outwardly-projecting bridle-front bracing-rib, 45 while the rear or under face of the appliance is smooth.

The single bridle-front which I have produced, composed of the bridle-front, the winker-brace, round from end to end, fixed 50 to the lower edge of the bridle-front, the center front billet-strap spliced to the bridle-front and projecting from the rear edge thereof, and the bridle-front and billet top fastened to the billet and bridle-front strap, 55 constitutes a new part for forming a bridle, and can be manufactured separately and carried in stock to sell to harness-makers to be used in their trade.

Now, having described my invention, what 60 I claim as new, and desire to secure by Letters Patent, is—

1. The combination set forth of the bridle front strap, the winker brace filling, the winker brace strap united to the bridle front 65 strap at the middle by the bridge and bent around the filling and stitched from end to end substantially as described.

2. The combination set forth of the bridle front strap; the winker brace filling; the 70 winker brace strap united to the bridle front strap at the middle and bent around the filling and stitched from end to end; the center front billet fastened to the bridle front strap, and the bridle front and billet top fastened 75 to the billet and bridle front strap.

OTTO RUF.
